UNITED STATES PATENT OFFICE.

DAVID P. DAVIS, OF ALLENDALE, NEW JERSEY, ASSIGNOR TO THE NEW YORK SAFETY STEAM POWER COMPANY, OF NEW YORK, N. Y.

BALANCE FOR STEAM-ENGINE ECCENTRICS.

SPECIFICATION forming part of Letters Patent No. 419,836, dated January 21, 1890.

Application filed May 10, 1889. Serial No. 310,271. (No model.)

To all whom it may concern:

Be it known that I, DAVID P. DAVIS, of Al-
lendale, in the county of Bergen and State of
New Jersey, have invented an Improved
5 Means for Balancing the Weight of the Ec-
centrics, Eccentric-Straps, and Connections
for Steam-Engines, of which the following is
a specification.

In wheel-governors for automatic engines
10 the centrifugal force of the governor weights
or balls has been made use of for shifting the
position of the center of the eccentric, and
thus varying its angularity in reference to
the center of the shaft and the crank-pin, so
15 as to admit more or less steam to the cylin-
der as the load upon the engine is varied. A
device of this character is represented in Let-
ters Patent No. 303,711, granted to me August
19, 1884. In the practical use of governors of
20 this character I have ascertained that after a
time more or less wear of the various parts
takes place and lost motion is produced, which
is multiplied at the eccentric, because of the
manner in which it is hung. If the speed of
25 the engine is sufficient, the centrifugal action
keeps the eccentric in position and nothing
detrimental occurs; but if the speed is slow
the weight of the eccentric and its connec-
tions causes them to drop slightly every time
30 they pass the center and a jerky action of
the valve takes place, causing an unequal dis-
tribution of the steam, and the effect is un-
pleasant, if not detrimental. By balancing
the weight of the eccentric and its connec-
35 tions this is entirely overcome, and the result
is smooth running at any speed.

In my improvement a counterpoise or bal-
ance on the frame of the engine is connected
40 to the eccentric-strap to lessen the wear upon
the eccentric and strap, and when used with
automatic governors upon the fly-wheel the
counterpoise prevents the looseness and lat-
eral movement of the eccentric and the false
or jerky movement of the valve.

45 In the drawings, Figure 1 is a side eleva-
tion illustrating my improvement as applied
to the eccentric of an engine, and Fig. 2 is an
end elevation of the same.

The main shaft A of the engine is supported
50 in the bed-frame and bearings B in any con-
venient manner, and the eccentric C is of the

proper size and construction, surrounding the
shaft A, but not directly connected to the
same; and D' represents the eccentric-rod.
The eccentric C is provided with an arm E,
55 at the end of which is a pivotal connection F
to the fly-wheel or belt-wheel G, and I re-
mark that the governor device is so connected
to the eccentric as to move the same laterally
and vary the stroke of the valve; but this gov-
ernor mechanism is not represented, as the
same may be such as shown in my aforesaid
patent, or it may be of any desired character.

My present improvement relates to the de-
vice made use of for balancing the weight of
the eccentric, the strap, and a portion of the
weight of the eccentric-rod. To effect this I
make use of a lever H, pivoted at 2 upon the
frame or bed B, and from the long arm of this
bent lever H a link K extends to the eccentric-
strap C', and it is preferable to fork the end of
the link, so that it receives into the fork the
strengthening-rib and hub upon the eccentric-
strap C', and the connecting-bolt 3 passes
through the forks of the link K and through
70 the hub upon the eccentric-strap C'. The
spring L is preferably a coiled steel wire or
rod connected at its ends to the heads M, and
these heads are perforated in the middle and
screw-threaded for the reception of the right
75 and left hand screw-rods N O, the rod O be-
ing pivoted at 5 to the short arm of the lever
H, and the rod N being pivoted at 6 upon the
frame or bed B, and there are lock-nuts around
the respective screw-rods N and O, adjacent
80 to the heads M. It will now be understood
that the spring L acts by tension upon the
bent lever H to cause the long end of said le-
ver and the link K to support the eccentric
strap and rod to any desired extent, and by
85 loosening the lock-nuts and revolving the
spring L and heads M the power of the spring
L can be varied to whatever extent desired,
and as the eccentric moves the eccentric-rod
and the strap C' backward and forward in
90 giving motion to the valve the spring L yields
more or less and the lever H turns upon its
pivot 2, and the link K swings back and forth
by the movement of the eccentric, and in con-
sequence of the weight of the eccentric being
95 supported through the action of the spring
and connections to the strap of the eccentric

such eccentric will not fall by its weight or give any false movement to the valve, and the governor is free to give the proper movement to the eccentric laterally in regulating the throw of the valve.

In engines that run at a slow speed the lever H may be extended and receive a movable weight, as shown by dotted lines in Fig. 1, so as to dispense with the spring, the weight being its equivalent.

I claim as my invention—

1. The combination, with the laterally-moving eccentric-strap and eccentric-rod, of the yielding support connected to the frame of the engine and the eccentric-strap, respectively, for sustaining the weight of the eccentric or a portion thereof, substantially as set forth.

2. The combination, with the laterally-moving eccentric-strap and eccentric-rod, of the lever H, spring L, and link K, such link K being pivoted to the strap of the eccentric and acting to sustain or partially sustain the weight of the eccentric without interfering with its movement, substantially as set forth. 20 25

3. The combination, with the eccentric, eccentric-rod, and strap, of the counterpoise lever H, and the link K, connecting the lever to the eccentric-strap, substantially as set forth.

Signed by me this 7th day of May, 1889.

DAVID P. DAVIS.
